SHOE SOLE

Lawrence W. Yaggi, Mishawaka, Ind., assignor to
United States Rubber Company, New York,
N. Y., a corporation of New Jersey

Application February 3, 1951, Serial No. 14,100

Term of patent 14 years

(Cl. D7—5)

To all whom it may concern:

Be it known that I, Lawrence W. Yaggi, a citizen of the United States, residing at Mishawaka, in the county of St. Joseph and State of Indiana, have invented a new, original, and ornamental Design for a Shoe Sole, of which the following is a specification, reference being had to the accompanying drawing, forming part thereof.

Fig. 1 is a bottom plan view of a shoe sole showing my new design;

Fig. 2 is a longitudinal sectional view taken on line 2—2 of Fig. 1.

I claim:

The ornamental design for a shoe sole, as shown and described.

LAWRENCE W. YAGGI.
